ATTORNEY

UNITED STATES PATENT OFFICE.

WILLIAM THOMAS, OF BROOKLYN, NEW YORK.

STEAM-BOX FOR FIXING DYES.

SPECIFICATION forming part of Letters Patent No. 314,629, dated March 31, 1885.

Application filed April 7, 1884. (No model.)

To all whom it may concern:

Be it known that I, WILLIAM THOMAS, a citizen of the United States, residing at Brooklyn, in the county of Kings and State of New York, have invented certain new and useful 5 Improvements in Steam-Boxes for Textile Printing and other Similar Purposes, of which the following is a specification.

My invention consists in so constructing a 10 steam-box that the goods will be shifted automatically in opposite directions to prevent uneven steaming.

The ordinary form of steam-box in use consists of a box of boiler-plate, with a door which 15 may be tightly closed and secured. Rails are laid on the floor of this box, and a carriage mounted on small wheels can be run in and out. This steaming-carriage consists of a frame-work having at the top a series of small 20 rolls crossing the carriage. Over these rolls the cloth is hung in perpend folds. In the best form of steam-box at present in use these rolls are connected at one end by a series of small gear-wheels, and are driven from one 25 end by a shaft and crank passing through a stuffing-box. These gears must be alternately reversed in their direction of rotation, and have always been turned by hand. The object of turning the rolls is to prevent the goods 30 hanging on them being unevenly steamed. Unless the cloth-sticks are turned, streaks of a different color will be developed where the goods hang on the sticks.

The object of my invention is to provide an 35 automatic device for turning the cloth sticks or rolls with an alternately-reversed motion, and thus provide for the perfectly-uniform action of the steam. For this purpose I attach to one side of the carriage a series of worm- 40 wheels independent of each other and equal in number to the number of cloth-sticks employed. These wheels are placed quite near together, leaving only sufficient room to avoid all risk of intermeshing. Running at right angles to these cloth-sticks in suitable bearings I place a horizontal shaft under the worm-wheels, and having at each wheel a section of an endless screw gearing with the wheel above it. The cloth-sticks are made square at one 45 end to fit square holes in the journals of the gear-wheels. The journals of the gear-wheels pass through or partly through the sides of

the carriage. The other ends of the cloth-sticks have a round end and collars. They rest in bearings upon the other side of the 55 carriage. The longitudinal shaft previously spoken of as attached to the carriage carries at the inner end a half-coupling, which is in line with a half-coupling on a continuation of this shaft which enters the steam-box through 60 a stuffing-box. To the outer end of the latter shaft is attached my automatic device for reversing the direction of motion of the worm-wheels and cloth-sticks. When the carriage is run into the steam-box, the coupling is connected and the shaft rotates, driving the worm-wheel. The shaft outside of the steam-box carries a double clutch, which can mesh with either one of two pulleys running loose on the shaft and driven in opposite directions. The 70 clutch slides freely on the shaft, but is forced to turn with it by means of a feather. On the same shaft with the clutch and pulleys is a portion of an endless screw gearing with a worm-wheel arc, which operates a system of 75 levers that throw each driving-pulley alternately into gear with the shaft, and consequently reverses the direction of rotation of the cloth-sticks after such a number of turns or portions of a turn as may be required. The 80 connection of the clutch and pulleys is made more secure by means of a counterpoise-weight attached to one of the levers of the system of levers.

In the drawings, Figure 1 is a view of a 85 portion of a steam-box, showing my devices. This figure is partly in section and partly in elevation. Fig. 2 is a plan view of the steam-carriage only. Figs. 3 and 4 are front and side views of another form of arc and lever 90 which may be used in place of the one shown in Fig. 1.

A indicates the walls of the steam-box, which are preferably of boiler-plate.

B is the steam-carriage, mounted upon 95 wheels C, running on rails R, placed on the bottom of the steam-box; or the wheels and rails may be placed higher up, if desired.

I are small worm gear-wheels attached to the side of the carriage, and by means of 100 square apertures in their journals to the cloth-sticks K, which have square ends at k' and collars at k.

G is a coupling, which may be of any con-

venient kind, but of such construction as to couple automatically when the carriage is pushed into the steam-box.

H is an ordinary stuffing-box, through which the shaft E passes. Upon the portion of the shaft E which is attached to the carriage are a series of portions of an endless screw, F², equal in numbers to the worm-wheels I and gearing with them. This shaft is supported 10 and turns in bearings attached to the side of the carriage, and not shown in the drawings. It is preferably constructed in sections of four, six, or more portions of the screw, and secured to each other by a mortise-and-tenon 15 joint, the object of so constructing the shaft being to permit of a certain flexibility in it within narrow limits. t t t, &c., are the folds of the goods hanging over the cloth-sticks.

L is a double-faced clutch, which can connect with either of the pulleys P P', which are loose on a continuation of the shaft E outside of the steam-box. Beyond the pulleys P P', on the same shaft with them, a portion of an endless screw, S, is cut. This gears 25 with a toothed arc, v², forming the upper portion of a lever, V, turning upon a pivot, v', and carrying at its lower end a pin, v³, which works in a small slot, n', in the end of a lever, N, which at its other end is pivoted by the 30 pivot m² to the lower end of another lever, M, rocking upon a pivot, m, and carrying at its upper end a pin which runs in a groove, l, in the clutch L. A short lever, O, is pivoted at o² to any convenient frame, to which frame 35 are also attached the pivots m and v'. A short slot, o', is cut in the lever O, in which a pin, n, attached to the lever N, works. The upper end of the lever O carries a weight, o³, which may be adjusted by sliding up or down the 40 lever.

In Figs. 3 and 4 a device is shown which may be substituted for the arc-lever V and slot n'. This device consists of a toothed arc, w, similar to the one shown in Fig. 1, but 45 having at its lower end another arc, w², pierced with holes w³, in which pins w⁵ may be inserted. This arc is pivoted at w' to a lever, w⁴, which can swing freely upon the pivot, but is limited in its motion by the pins inserted on 50 each side of it in the arc w².

The action of the apparatus is as follows: The goods to be steamed are hung on the cloth-sticks, which have been inserted in the worm-wheels I. The carriage is run into the steam-box and the door closed. The coupling G connects automatically, and the pulleys P P' being connected by proper belts with a motive power, the shaft E begins to turn, and by means of the screw-threads and worm-wheels 55 the cloth runs over the cloth-sticks in one direction. In the meantime the screw-thread S is acting upon the toothed arc v² and rotating the lever V, and carrying the pin v³ along the slot n', without moving any other part, until it 60 strikes against one end of the slot. It then forces the rod N to move, and with it the le-

ver M, which, by a pin working in a groove in the double clutch L, pushes it out of gear with one pulley and into gear with another pulley running in the opposite direction. This contact is made secure and certain by means of the weighted lever-arm O. The shaft E now rotates in the opposite direction, and the cloth-sticks also turn in the opposite direction, running the cloth back as much as it had previously been turned forward. The reason for thus reversing the direction of rotation of the cloth-sticks is evident, as the cloth would soon be run out of the carriage if the motion continued in one direction. The amount of travel 80 of the goods over the cloth-sticks is regulated by the length of the slot n' in the lever N, and this may be regulated by set-screws or otherwise; or, in case the alternative arrangement shown in Figs. 3 and 4 is used, the time during which the shaft E shall rotate in one direction is limited by the distance apart of the pins in the arc w².

Having now fully described my invention, what I claim, and desire to secure by Letters 90 Patent, is—

1. In an apparatus for steaming dyed fabrics, and using a carriage capable of running in and out of a boiler or steam-tight inclosure, the said carriage being provided with cloth-sticks suitably geared to a shaft attached to the carriage and automatically connected to a shaft outside of the boiler, the combination of the pulleys running loose on the said shaft, a double clutch prevented from rotating with the shaft by means of a feather, but capable of sliding longitudinally thereon, a pin working in a circumferential groove in said clutch, a toothed arc or sector gearing with a worm on the pulley-shaft and pivoted to the frame 100 of the machine, and suitable levers and counter-weight to connect the toothed arc with the pin and clutch before mentioned, all substantially as and for the purpose specified.

2. In an apparatus for steaming dyed fabrics, the combination of a boiler, carriage, cloth-sticks geared to a longitudinal shaft, automatic coupling, exterior shaft, loose pulleys driven in opposite directions, sliding double clutch, worm or screw-thread on shaft, pivoted toothed arc gearing with worm on shaft, and system of levers connecting toothed arc with clutch, substantially as shown and described.

3. In an apparatus for steaming dyed fabrics, the combination of the carriage B, boiler A, cloth-sticks K, gear-wheel I, shaft E, coupling G, loose pulleys P P', clutch L, worm S, toothed pivoted arc V, levers M, O, and N, and counter-weight o³, all arranged substantially 125 as shown and described.

In witness whereof I have hereunto set my hand.

WILLIAM THOMAS.
